Specification of Letters Patent.

Patented May 4, 1915.

Application filed March 7, 1910, Serial No. 547,721. Renewed September 23, 1914. Serial No. 863,221.

To all whom it may concern:

Be it known that we, JAMES W. AMES, a citizen of the United States, residing at Montclair, in the county of Essex and State 5 of New Jersey, and LOUIS J. BATZLE, a citizen of the United States, residing at Bayonne, in the county of Hudson and State of New Jersey, have invented certain new and useful Improvements in Spike-Machines, of 10 which the following is a full, clear, and exact specification.

Our invention relates to machines for forming spikes, such as railroad spikes, and to the method whereby such spikes are 15 formed.

The invention is illustrated in connection with a type of machine known as the Cary machine, to which it is particularly applicable, and by means of which said machine 20 is rendered capable of automatic action, whereby its capacity is greatly increased. Our invention, however, is not limited in its application to such particular type of machine, but is applicable, also, to other types 25 of machines for forming spikes and analogous articles.

In the use of the ordinary type of such Cary machine, the stock is fed in by hand and a cutter moves horizontally across the 30 line of feed and cuts the blank off, leaving a vertical fin on that part of the stock which is to form the head of the next spike. To insure uniformity in the two sides of the spike, it is essential that the stock should 35 be given a quarter turn before the next blank is cut off, and this operation, which is performed by hand, is an obstacle to the automatic operation of the machine. The application of our invention to such machine 40 obviates the necessity for turning the stock in the machine and also finishes the entire spike, including the point, in one operation.

These objects we attain by imparting a new function to the movable point-forming 45 die; to wit, that of serving the newly-formed spike from the stock, which function is accomplished by giving the said die a capacity for lateral movement substantially in the direction of the feed and by providing 50 means whereby said die is given a movement which severs the stock from the spike and finishes the point of the spike, and by providing a stationary bottom-pointing die to

coöperate therewith. The steps of the method whereby this result is accomplished 55 are as follows: (1) The stock from which the spike is to be formed is suitably clamped against the bottom dies and chills; (2) The body-pressing and point-forming dies are then brought forcibly down into contact 60 with said stock, to shape the same and press a point thereon; (3) The head-forming die is forced against the blank, which movement may begin before the point-forming die has ceased its first movement; (4) The point- 65 forming die as it completes its pressing movement is moved against the stock, severing it from the newly-made spike; and (5) The finished spike is then ejected.

The material used for forming the spikes 70 is usually heated to obtain the best results and the parts of the dies that come in contact therewith, as well as those parts that receive excessive wear, are usually hardened.

One embodiment of our invention is 75 shown in the accompanying drawings which illustrate the same applied to a spike machine of the Cary type, and in connection therewith our new method may be easily understood.

In the said drawings Figure 1 is a front elevation of the said machine. Fig. 2 is a rear elevation thereof. Fig. 3 is a side elevation, looking at the machine from the right of Fig. 1. Fig. 4 is a plan view of 85 the machine, parts being omitted for clearness. Fig. 5 is a detail of the dies and chills; and Fig. 6 is a sectional detail of the same parts on the line a—a of Fig. 1, looking toward the left.

The machine has a base 1, upon which, at the rear of the machine, are standards 2, 3, in which the driving shaft 4 is borne. This shaft has fixed thereon a driving-pulley 5, and a balance-wheel 6.

A frame 7 is secured to the base 1, in this instance being cast integral therewith, and within said frame are secured the stationary bottom dies and chills, by means of threaded bolts 8, which are passed through threaded 100 openings in the side of said frame. The said dies and chills comprise the gripping and head-forming lipped die 9, the lipped-chill 10, and the pointing chill 11. These are secured laterally on one side by the 105 frame 7, and on the other by a block 12,

against which the bolts 8 bear. A plate 13 is bolted to the top of the pointing-chill 11, and at the other end receives a bolt which passes through a slot 14 in the block 12. 5 This plate 13 is to prevent rising of the dies and chills. The said dies and chills 9, 10, 11, may be kept cool by water dropped on them from above, which is not shown.

A bottom-pointing die 15 is inserted from 10 the front of the machine and held in place by a wedge 16, between abutments 17, 18, on the base. At its front upper surface this die is level with the blank-receiving lip on chill 10 and is beveled to form the lower 15 half of the point. The bevel terminates at cutting-shoulder 19, which serves to cut the stock in coöperation with a stationary bottom-pointing die to be described. A block 74 supports the stock in front of the pointing-dies. 20

A moving lipped gripping-die 20 (Fig. 4), is secured in a movable frame 21, by set-screws 22, which pass through threaded holes on said frame and bear against a gripping-chill 23, which lies at one side of said gripping-die, and keeps the stock from spreading and warping while being pointed and headed. On the other side is a block 24, bolted to which is a plate 71, which 30 passes over the top of the die and prevents its rising.

The frame 21 is mounted on the end of a bifurcated rocking-arm 25, which is journaled on a shaft 40, having bearings in 35 brackets 26, 27, depending from cross-bars forming part of the base of the machine. An operating-arm 28 is attached to said movable frame 21 and projects toward the rear of the machine therefrom, rising so 40 that its rear end is above the driving shaft and within the path of a cam-wheel 29 on the driving-shaft. This cam-wheel is offset axially on one side, whereby, as it revolves, it imparts a sidewise motion to the 45 operating-arm 28 and causes the moving gripping-die 20 to move in the arc of a circle around the shaft 40 of the rocking-arm 25, and the lip on die 20 then passes over the stock, gripping the stock 70 between dies 20 and 9, and between chills 24 and 10 and 11. 50 The completion of the revolution of the cam-wheel 29 releases the operating-arm 28, and the frame 21 returns by gravity to its initial position. The said gripping-die 20 and chill 55 24 press the stock firmly against gripping-chill and dies 9, 10, and 11, and serve to hold the stock while the head and point are being formed and prevent warping or spreading.

The movable pointing-die 30 has its point 60 beveled counted to the bevel on the stationary bottom-pointer 15 and is held next to the movable body-die 31, in a frame 32, by bolts 72 passing through the frame. The frame 32 is supported in a rocking cross-head 33, 65 and enters a recess 34 formed in the under-

side thereof. Flanges 35 project laterally from both sides of said frame and rest on plates 36, bolted to the underside of said cross-head and permitting the frame to slide crosswise relative to the head. A flat spring 70 37 is bolted to the crosshead and returns the frame to its place when it is moved forward. The rearward movement of the frame may be stopped by any suitable stop, as by a plate 38 on the rear wall of the cross-head (Fig. 6). 75

The cross-head 33 has rocking-arms 39, 39^a, which have bearings on short shafts journaled in posts 41, 42, at the front of the machine, and the cross-head likewise has an operating-arm 43, which projects rearwardly of the machine and over the driving shaft, where it is connected by pitman 44, to a crank-pin on crank-wheel 45, which is fixed to the driving-shaft 4. Bolts 46, 47, are provided, which pass through threaded holes in frame 34 and engage the rear of dies 30, 31, to support and adjust same, and these bolts slide in a slot 48 in the cross-head 33. The said parts are omitted from the plan view of the machine (Fig. 4) for clearness in illustrating the parts that lie beneath them, but are clearly illustrated in the remaining figures. 85

In the particular embodiment illustrated the pointing-die moves in a direction transverse of the body of the spike to be formed around the pivots of the cross-head 33, and said die likewise has a movement lengthwise of said spike caused by the sliding of the frame forward in the cross-head. By means of such movements, as the pointing-die is brought down upon the stock by the rocking of the operating arm, it cuts a point upon the stock by the coöperation of the bottom-pointing die 15, and as a lengthwise movement is imparted thereto just prior to the completion of its transverse movement, it will sever the newly-pointed spike from the stock at the same time die 31 presses and strengthens the body of the spike. 95

The movable gripping-die has its side toward the front of the machine beveled at 49 so as to narrow its face, thereby permitting the movable body-die 31 to pass. The movable heading-die 50 is suitably shaped on its face to form the head of the spike and is held in a recess 51, in a rocking-arm 52 (seen in dotted lines in Fig. 3), which is actuated by an operating-arm 54 which passes rearwardly and over eccentric lug 55, which is fixed to the driving-shaft and revolves therewith. Rocking-arm 52 turns on a shaft 56 (seen in dotted lines in Fig. 2), supported in brackets 57, 58, depending from the side bars in the base. 105

Arrows in the different views show the direction of revolution of the driving-shaft, from which it will be seen that as the lug 55 is turned and engages operating arm 54, the heading-die is driven forward upon the 110 130

stock and presses same toward the front of the machine and into the recesses on the stationary and movable heading dies.

- An important feature of our invention is 5 the supplemental or sliding movement imparted to the movable pointing-die. Such movement may be imparted in a number of ways and one desirable manner of so imparting it is shown in the drawings, where such 10 movement is given by the movable heading-die. A block 59 is suitably secured to the heading-die, as by being bolted thereto, and a strap 60 is then passed over the said block and is bolted to side-posts 73, projecting upwardly from rocking-arm 52, whereby the 15 said parts are securely assembled. The rear and side walls of recess 51 and the strap 60 hold the heading die and block and enable them to exert the proper pressure.
- 20 The block 59 is so adjusted that preferably it will engage the sliding-frame 32 before the pointing-die has completed its circular movement and, of course, before the heading-die has completed the head. A 25 slight movement of the heading-die will then remain, preferably about $\frac{1}{4}$ to $\frac{3}{8}$ inch, which will cause the pointing-die to have an equal extent of movement transverse of the cross-head 33, which will be sufficient to complete 30 the point and, in coöperation with bottom-die 15, to sever the newly-made spike from the stock. The best results have been obtained by having the latter part of the supplemental or sliding motion of the pointing-die 35 take place after the movement of said die in the arc of a circle has been completed, and when the said movable pointing-die is in its lowest position, where it is substantially over the bottom-pointing die. The 40 balance of the supplemental motion will carry the movable pointing-die slightly past the stationary or bottom-pointing die and thereby completely sever the stock.
- 45 After the heading-die has performed its work and the lug on the driving-shaft has passed its operating-arm, the rocking-frame falls back by gravity and is received on a cross-bar of the base of the machine. The finished spike is then ejected by an ejector 50 61, which works crosswise of the machine and the front end of which passes through a slot 62, in a stationary chill 10, and which ejector by its forward movement discharges the finished spike from the dies. Said 55 ejector is operated by a lever 63, turning on a pivot 64, fixed to the base and having an upwardly-turned end which passes within the path of cam 65, on cam-wheel 66, carried by the driving-shaft.
- 60 A retracting-spring 67 is secured at the top of post 3, at the rear of the machine, and is attached to an eye 68, on the lever 63, by hook 69, and serves to retract the ejector after the passage of cam 65 by the 65 end of lever 63.

We have not illustrated an automatic feed in connection with our invention, as the particular kind of feed used forms no part of our present invention and such automatic feeds are well known.

The operation of our improved machine and our improved method of forming spikes are as follows: The stock is fed from the front of the machine to the bottom dies and chills, where it is clamped in position by the moving gripping-die and chill. The stock being thus firmly held between the upper and lower gripping-dies, the body-pressing and point-forming die approach the stock and press it against the bottom dies and chills, and the movable point-forming die in coöperation with the stationary point-forming die begin forming the point. This is accomplished by a cutting action whereby the metal at the point is cut. Before the moving pointing-die has completed its stroke, the moving header, which has in the meantime been moved forwardly in the performance of its head-forming function, has progressed so far that its block engages the frame carrying the pointing-die and gives the same a slight forward movement of $\frac{1}{4}$ to $\frac{3}{8}$ inch, according to adjustment. The latter part of this movement—about one-half of it—takes place after the movable pointing-die has completed its movement in the arc of a circle, and when it is at its lower point. The said supplemental motion, therefore, has the effect of moving the pointing die when in lowest position lengthwise of the spike which will sever the stock in connection with the bottom-pointing die. By this time the head is completed and said supplemental movement of the pointing-die completes the point and severs the stock. The moving dies then withdraw and the ejecting mechanism discharges the completed spike.

We claim:

1. In a spike-forming machine, an upper-pointing-die, a bottom-pointing-die, means for moving one of said dies in a direction transverse of the stock, and means for imparting a supplemental movement thereto lengthwise of the stock after the pointing-dies have formed the point on the spike being formed, thereby severing the stock by a pulling apart of the web left between said stock and formed spike. 110
2. In a spike-forming machine, an upper-pointing-die, a bottom-pointing-die, means for moving the upper die toward the stock to form a point on the portion thereof to be formed into a spike, with a web between said portion and the stock and means for imparting a supplemental movement to said upper die lengthwise of the stock, thereby severing the stock from the portion forming the spike by a pulling apart of the web between said stock and said portion thereof. 115
3. In a spike-forming machine, grippers 120

- for holding the stock, an upper-pointing-die and means for moving same toward the stock to form the point on the portion thereof to be formed into a spike, with a web between said portion and the stock, means for permitting said die to have a supplemental movement lengthwise of the stock, a heading-die and means for operating same, and means operated by the movement of said heading-die for giving a supplemental movement to said pointing-die to sever said stock and said portion thereof by a pulling apart of the web left between said stock and said portion thereof.
4. In a spike machine, a cross-head and means for moving same toward the stock, a frame mounted in said cross-head and movable lengthwise therein, a pointing-die supported in said frame adapted to form a point on the portion of said stock to be formed into a spike, with a web between said portion and the stock, a movable heading-die, and an abutment carried thereby adapted to engage said frame and impart said supplemental movement thereto to sever said stock and said portion thereof by a pulling apart of the web left between said stock and said portion thereof.
5. In a spike-machine, a cross-head, pivotal supports therefor, means for moving said cross-head toward the stock, a frame mounted in said cross-head and movable lengthwise therein, a pointing-die carried by said frame adapted to form a point on the portion of said stock to be formed into a spike, with a web between said portion and the stock, and means for imparting a supplemental movement to said pointing-die after the same has completed its movement toward said stock, to sever said stock and said portion thereof by a pulling apart of the web left between said stock and said portion thereof.
6. In a spike-machine, a cross-head, pivoted supports therefor, means for moving said cross-head toward the stock, a frame mounted in said cross-head and movable therein, means for returning same to normal position, a pointing-die carried by said frame adapted to form a point on the portion of said stock to be formed into a spike, with a web between said portion and the stock, means for adjusting same in the frame, and means for imparting a supplemental movement to said pointing die after the same has completed its movement toward said stock, to sever said stock and said portion thereof by a pulling apart of the web left between said stock and said portion thereof.
7. In a spike-machine, a cross-head, a pivotal support therefor, means for moving said cross-head toward the stock, a frame mounted in said cross-head and movable therein, a movable pointing-die carried by said frame adapted to form a point on the

portion of said stock to be formed into a spike, with a web between said portion and the stock, a coöperating stationary pointing-die, gripping devices for the stock, a heading-die and means for moving same toward the stock, and means connected with said heading-die for moving said movable pointing-die in a direction lengthwise of the stock, whereby the stock is severed from the portion forming the spike by a pulling apart of the web between said stock and said portion thereof.

8. In a spike-machine, a cross-head, a pivotal support therefor, means for moving said cross-head toward the stock, a frame mounted in said cross-head and movable lengthwise therein, a movable pointing-die carried by said frame adapted to form a point on the portion of said stock to be formed into a spike, with a web between said portion and the stock, gripping devices for the stock, a co-operating stationary pointing-die, a heading-die and means for operating same, and means connected with said heading-die for imparting a movement to said movable pointing-die lengthwise of the stock before the completion of the movement of said heading-die and substantially upon the movable pointing-die completing its first-mentioned movement to sever said stock and said portion thereof by a pulling apart of the web left between said stock and said portion thereof.

9. In a spike-machine, body-gripping and chilling-dies, a bottom beveled pointing-die, a cutting-shoulder thereon, a movable cross-head, a pointing-die carried thereby and movable relative thereto adapted to form a point on the portion of said stock to be formed into a spike, with a web between said portion and the stock, means for causing said cross-head to approach the stock, a heading-die, and means connected with said heading-die for causing a movement of said pointing-die relative to said cross-head substantially upon the pointing-die having completed its first movement, whereby the stock is severed from the portion forming the spike by a pulling apart of the web between said stock and said portion thereof.

10. In a spike-machine, body-gripping and chilling-dies, a bottom beveled pointing-die, a cutting-shoulder thereon, a pivoted cross-head movable in the arc of a circle toward the stock, a frame carried thereby and movable relatively thereto, a pointing-die adjustably mounted in said frame adapted to form a point on the portion of said stock to be formed into a spike, with a web between said portion and the stock, means for operating said cross-head, a heading-die, operating means therefor, an abutment movable with said heading-die and adapted to move the said frame before

the heading-die has completed its operation and substantially upon the movable pointing-die having completed its first-mentioned movement, whereby the stock is severed from the portion forming the spike by a pulling apart of the web between said stock and said portion thereof, and means for ejecting the finished spike.

11. In a spike-machine, a plurality of 10 pointing-dies, means for causing relative movement thereof toward each other to form a point on a portion of a piece of stock to be formed into a spike with a web between said portion and the stock, and 15 means for imparting a supplemental longitudinal movement to one of said pointing dies, to sever the stock and said portion thereof by a pulling apart of the web left between said stock and said portion thereof.
- 20 12. In a spike-forming machine, a plural-

ity of coöperating pointing-dies, means for causing one of said dies to move toward the other in a direction transverse of the stock, means for causing a supplemental movement of said moving die in a direction 25 lengthwise of the stock which continues after the cessation of said first movement, and said movable die terminating its first movement in a plane substantially level with the cutting edge on the coöperating 30 die.

In witness whereof we have hereunto set our hands in the presence of two subscribing witnesses.
